CLAIM

We claim the ornamental design for work platform, as shown and described.

DESCRIPTION

FIG. 1 is an isometric view of a work platform in an open position.

FIG. 2 is a top plan view thereof.

FIG. 3 is a side elevation view thereof, the view from the other side being a mirror image of FIG. 3.

FIG. 4 is an end view thereof, the view from the other end being a mirror image of FIG. 4.

FIG. 5 is a bottom plan view thereof.

FIG. 6 is an isometric view thereof in a closed position.

FIG. 7 is a top plan view thereof in a closed position.

FIG. 8 is a side elevation view thereof in a closed position, the view from the other side being a mirror image of FIG. 8.

FIG. 9 is a bottom view thereof in a closed position; and, FIG. 10 is an end elevation view thereof in a closed position, the view from the other end being a mirror image of FIG. 10.

1 Claim, 8 Drawing Sheets
